UNITED STATES PATENT OFFICE.

GEORGE KINGSTON, OF KOKOMO, INDIANA.

CARBURETOR.

Application filed February 19, 1923. Serial No. 619,803.

This invention relates to a carburetor and particularly to a carburetor which is provided with effective and conveniently accessible low speed adjusting means.

5 Variations in the characteristics of individual motors requires that fuel mixture of different quality and quantity be provided to assure efficient operation thereof at low speeds. It is also often desirable that the 10 low speed adjustments be changed after the carburetor is installed because of changes in weather conditions or in the fuel used.

It is an important object therefore of this 15 invention to provide a carburetor wherein an adjustment for proper low speed operation may be quickly and conveniently made.

It is a further important object of this invention to provide a carburetor wherein a plurality of adjusting means which are 20 separately operable from the outside of the carburetor extend to a common point within the carburetor.

Other and further important objects of the 25 present invention will be apparent from the disclosures in the specification and the accompanying drawings.

The invention (in a preferred form) is shown on the drawings and hereinafter more fully described.

30 On the drawings:

Figure 1 is a top plan view of a carburetor embodying the principles of the present invention.

Figure 2 is a side elevation of the carburetor.

Figure 3 is a section on the line 3-3 of Figure 2, with parts in elevation.

Figure 4 is a section on the line 4-4 of Figure 1, looking in the direction indicated 40 by the arrows, and with parts shown in elevation.

Figure 5 is a section on the line 4-4 of Figure 1, looking in the direction opposite to that indicated by the arrows and with 45 parts shown in elevation.

As shown on the drawings:

The reference numeral 1 indicates a cast metal carburetor casing which is cored to provide an air inlet 2, controlled by a usual choke valve 2^a, a mixing chamber 3, and a mixture outlet 4. A usual flange 5 is formed on the casing 1 adjacent the mixture outlet 4 to afford a connection with an intake manifold and the flow of fuel mixture

through the mixture outlet is controlled in 55 the usual manner by a butterfly throttle valve 6 which is pivoted in the casing 1 and operable from the outside thereof by a usual lever 7.

Extending downwardly from the floor of 60 the mixing chamber is an integral projecting member 8 which has its lower end reduced and threaded as indicated at 9, and engaged over said reduced and threaded portion 9 is a cup member 10 which affords a 65 supply chamber for liquid fuel and the upper end of which abuts a seat formed in a suitable flange 11 which is integral with the casing 1. Said cup member 10 is held in adjusted position by means of a nut 12 engaged outside the same on the threaded portion 9, the tightening of said nut 12 forcing the inside of said cup member 10 against a gasket 13 interposed between said cup member and the shoulder formed on 70 the member 8 at the junction thereof with the reduced portion 9. Liquid fuel is supplied to the fuel chamber afforded by the cup member 10 through a passage 14 formed in the casing 1 and communicating 75 with a suitable fuel connection 15 leading to a source of supply. The flow of fuel through the passage 14 is regulated by a valve 16 which is controlled in the usual manner by a float 17 mounted inside the 80 cup member 10. An integral dividing wall 18 is formed in the casing 1 between the mixing chamber 3 and the mixture outlet 4, and the flow of fuel mixture through a passage in said dividing wall is controlled by 85 a pivoted, weighted valve 19 which seats on a flange 20, formed in said dividing wall around the opening therein, and which is adapted to be lifted from its seat by the flow of fuel mixture, the opening movement of the valve being limited by the contact of a portion 21 thereon with a boss 22 integral with the casing 1 and projecting 90 into the mixture outlet 4.

Liquid fuel is admitted to the mixing 100 chamber from the fuel supply chamber afforded by the cup member 10 through a passage 23 which is formed in the member 8 and the lower end of which opens into said fuel supply chamber. The flow of 105 liquid fuel through said passage 23 is controlled by a needle valve 24 which is adjustably mounted in an internally threaded

sleeve nut 25 threaded in the upper end of the casing 1. In order that said needle valve 24 may be conveniently rotated for adjustment from the outside of the carburetor, a knurled adjusting nut 26 is secured to the upper end thereof.

As will be noted from an examination of Figures 3, 4 and 5, the needle valve 24 is positioned at an angle relative to the vertical axis of the carburetor and extends through a passage formed in the wall 18. The upper end of the passage 23 is enlarged to receive a tubular member 27 which is open at each end and the axis of which converges to meet the axis of the needle valve 24. As will be noted in Figure 5, said open-ended tubular member 27 is slotted at its upper end to allow the needle valve 24 to be engaged therethrough and to enter the upper end of the passage 23.

In order to obviate the possibility of flooding the mixing chamber 3 an overflow passage 29 is formed in the member 8 leading to the outside of the carburetor and having an open-end tube 30 secured in its upper end and projecting into the mixing chamber for a short distance above the end of the tubular member 27. A usual drain valve 31 is secured in the floor of the cup member 10 for the purpose of draining the fuel supply chamber when desired.

Coaxial with the tubular member 27 and having its lower end separated a short distance from the upper end of said tubular member is a tubular member 32 which is threaded at 33 for engagement with a threaded opening in the wall 18 and said tubular member 32 is provided at its upper end with a plurality of apertures 35 opening into the mixture outlet 4. Secured to or integral with the upper end of the tubular member 32 is a stem 36 which extends outwardly through and is rotatably mounted in a sleeve nut 37 which is threaded in the upper side of the casing 1. In order to facilitate the rotation of said stem 36 from the outside of the carburetor, the upper end thereof is provided with a knurled adjusting nut 38. It will be noted that the tubular member 32 affords a by-pass between the mixing chamber 3 and the mixture outlet 4 around the valve 19 and said by-pass affords a path for the flow of fuel mixture when the engine is idling or running at low speeds. The quality of the fuel mixture flowing through the tubular member 32 may be adjusted by axially adjusting said tubular member, such axial adjustment being effected by rotation thereof through the stem 36 and adjusting nut 38. It will, of course, be apparent that as the lower end of the tubular member 32 is moved into proximity with the upper end of the tubular member 27, less air will be admitted to the by-pass and a richer mixture for

idling and low speed operation will, of course, be provided. The converse occurs when the lower end of the tube 32 is moved away from the upper end of the tubular member 27, under these conditions more air being admitted and a leaner idling or low speed mixture being provided, the mixture in each case being discharged into the mixture outlet 4 through the apertures 35.

It will be apparent from the foregoing that this invention provides a carburetor structure wherein an accurate adjustment for low speed operating conditions may be conveniently made from the outside of the carburetor. This adjustment may be effected without in any way disturbing the high speed adjustment which is made by properly positioning the needle valve 24, and the provision thereof makes possible the accurate adaptation of the carburetor to individual motors having varying operating characteristics. In the operation of the carburetor, at low or idling speeds the automatic valve 19 remains seated due to its own weight and the fuel and air mixture requirements of the engine are met by the flow through the bypass tube 32 and port 35. It will be evident that screwing down this tube will reduce the area for the admission of air between the tubes 27 and 32, without affecting the fuel supply, thereby effecting the production of a richer mixture. As the throttle is opened the suction therebeneath reaches a point sufficient to lift the seated valve 19, opening up a large air passage which will draw fuel over the edge of the tube 27 in addition to that fuel carried up the tube 32, so that for high speed the fuel may be controlled by the needle valve 24. In other words the needle valve is adjusted for high speed requirements and the tube 32 is adjusted to care for the low speed requirements, the latter adjustment having only a slight effect on the high speed adjustment.

It will be noted that the adjusting means are simple and may be economically manufactured, and that they do not in any way interfere with the normal operation of the carburetor.

I am aware that numerous details of construction may be varied through a wide range without departing from the principles of this invention, and I therefore do not purpose limiting the patent granted, otherwise than necessitated by the prior art.

I claim as my invention:

1. In a carburetor, a mixing chamber, a fuel inlet, an air inlet, a mixture outlet, a throttle, an automatic valve between the mixing chamber and the mixture outlet, a tube extending from the mixing chamber to the mixture outlet and forming a by-pass around said valve, said tube having a plurality of apertures in the portion thereof

extending into the mixture outlet, and means for adjusting the tube longitudinally from the outside of the carburetor.

2. In a carburetor, a mixing chamber, a fuel inlet, a tube surrounding the fuel inlet, an air inlet, a mixture outlet, a throttle valve, an automatic valve between the mixing chamber and the mixture outlet, a second tube coaxial with the first tube and affording a by-pass around said automatic valve, and means for adjusting the position of said second tube relative to the first tube from the outside of the carburetor.

3. In a carburetor, an air inlet, a mixing chamber, a mixture outlet, a fuel inlet, a slotted tube surrounding the fuel inlet, a needle valve extending from the outside of the carburetor through the slot in said tube and acting to control the flow of

fuel from said fuel inlet, a second tube adjustable from the outside of the carburetor and coaxial with said first tube, said second tube opening into said mixture outlet and said mixing chamber.

4. In a carburetor, an air inlet, a mixing chamber, a mixture outlet, a fuel inlet, a tube surrounding the fuel inlet, a needle valve extending from the outside of the carburetor through an opening in said tube and acting to control the flow of fuel from said fuel inlet, a second tube adjustable from the outside of the carburetor and coaxial with said first tube, said second tube opening into said mixture outlet and said mixing chamber.

In testimony whereof I have hereunto subscribed my name.

GEORGE KINGSTON.
